UNITED STATES PATENT OFFICE.

HARRY L. GORDON, OF NEW YORK, N. Y.

ANTIGLARE ATTACHMENT FOR HEADLIGHTS.

Application filed September 15, 1925. Serial No. 56,500.

This invention relates to an antiglare attachment for headlights, and has for its object the provision of simple and efficient means for preventing the headlights of motor vehicles from glaring, or blinding the vision of a person in an approaching vehicle, or a person crossing the street in the path of the oncoming motor vehicle.

With this and other objects in view, my invention comprises certain novel constructions, combinations, and arrangements of parts as will be hereinafter fully described, illustrated in the accompanying drawings, and more particularly pointed out in the appended claims.

In the drawings:—

Figure 1 is a vertical sectional view through my attachment and an ordinary type of a headlight.

Figure 2 is a view in elevation of the outer plate.

Figure 3 is a view in elevation of the inner plate.

Figure 4 is a perspective view of the extension plate.

Figure 5 is a fragmentary perspective view of the inner and outer plates shown in an assembled position.

Figure 6 is a fragmentary perspective view of a headlight with my attachment in position thereon.

Figure 7 is a fragmentary vertical sectional view of the device, showing an extension plate thereon.

Referring to the drawings by numerals, 1 designates the headlight which is provided with a grooved portion 2, in which is seated the cord like packing 3. My attachment is placed between the glass 4 and the packing 3, with the pointed prongs 5^a of the outer plate 6 sunk into the packing 3 (Fig. 6) for holding the outer plate from shifting its correct position within the headlight 1.

The outer plate 6 is provided with blades 7, and with the prongs 5, as well as struck out ears 8. Each prong 5 is provided with shouldered portions 9 that bear against the inner face of the inner plate 10 when the inner and outer plates are assembled (Fig. 5); the extreme outer ends of prongs 5 are bent up at right angles (Figs. 1 and 7) securely holding the two plates in an assembled position. It will, therefore, be seen that the prongs 5 are cut or struck out from the plate 6 and are partly inserted

through the elongated slots 11 (Fig. 3) of inner plate 10, with the shouldered portions 9 of the prongs 5 bearing against the inner plate, holding said plates in spaced position. 60

The inner plate 10 is provided with blades 12 that are arranged in substantially a V-shaped position, the object being to place these blades at an angle to the plane in which the blades 7 of the front plate are positioned, so as to break up the rays cast from bulb 13 and throw these broken up or "chopped" rays against the deflecting blades 7, and thence onto the road way, thereby eliminating completely the glaring effect of 70 an ordinary headlight.

It is to be noted that the maximum amount of benefit is obtained by having a plurality of assembled plates, one of which is provided with blades placed at an angle 75 to the plane of the other blades, as is clearly shown in Figure 6; further, the blades of the inner plate are arranged preferably in a V-shaped position, giving the maximum amount of effect, to the breaking 80 of the rays in their reflection against the blades of the outer plate, for the purpose hereinbefore specified.

The outer plate is held securely in its assembled position by said prongs 5^a sunk 85 in the packing 3, as hereinbefore stated.

I use extension plates 14 in case my attachment is placed in a larger lamp; that is, by using extension plates 14, my device can be made to suit any size lamp. This 90 plate 14 is placed at the top and bottom of the outer plate 6, and is similarly constructed, so that it will only be necessary to describe one of the extension plates. The body 15 of the plate is provided near opposite ends with a series of elongated slots 16 into which slots 16 are placed the ears 8 (Fig. 7) which ears are then bent up against the plate to hold the plate securely upon the outer plate 6. This extension plate 14 is 100 provided with the packing penetrating prongs 5^a just the same as the outer plate 6, and plate 14 is also provided with spacing ears 17 that are adapted to fit snugly against the inner face of the inner shell 18 for holding my device snugly and firmly within the headlight 1. By moving the plate 15 up or down upon the outer plate 6, and placing the ears 8 in different slots 16, the outer plate (and my device) can be 105 made to fit or accommodate itself to different size headlights. 110

It is to be noted that the blades of the plates can be "opened" or "closed" more tightly together, depending upon the will of the constructor to permit greater or less amount of rays to pass between the blades. Further, any number of plates may be assembled together, one behind the other, but I have found by experience that the preferred embodiment of my invention, as shown in the accompanying drawings, is preferable.

While I have described the preferred embodiment of my invention and illustrated the same in the accompanying drawings, certain minor changes or alterations may appear to one skilled in the art to which this invention relates and I, therefore, reserve the right to make such changes or alterations as shall fairly fall within the scope of the appended claims.

What I claim is:—

1. In an antiglare attachment for headlights, the combination of a pair of plates provided with inwardly extending blades on their contiguous faces, one of said plates provided with prongs having shoulders, said prongs positioned between the plates and extending through one of the plates with their shoulders bearing against the inner face of one of the plates, said shoulders on the prongs spacing the blades apart, and means formed on one of the plates for holding the device against shifting its position when placed upon a headlight.
2. In an antiglare attachment for headlights, the combination of a plate provided with blades, said plate provided with ears, an extension plate provided with a plurality of slots against said first mentioned plate, and said ears adapted to be placed in different slots of said extension plate for

placing the extension plate in different positions upon said first mentioned plate.

3. In an antiglare attachment for headlights, the combination of a pair of plates having their outer faces smooth and their inner faces provided with inwardly extending blades, spacing means carried by said plates near their edges and provided with shoulders bearing against the inner face of one of the plates, and said spacing means being secured at one end to one of the plates and having their opposite end extending through the other plate and bent down thereon, whereby the blades are held in a spaced relation to each other.

4. In an antiglare attachment for headlights, the combination of a vertical headlight fitting plate provided with blades, said plate provided with integral outwardly extending ears, an extension plate against said first mentioned plate, said extension plate provided with sets of elongated apertures, each set comprising a plurality of vertically aligned apertures and registering with an ear, and said ears adapted to be placed through different apertures in said sets for holding the extension plate in an adjusted position upon said first mentioned plate.

5. In an antiglare attachment for headlights, the combination of a pair of vertically positioned plates provided only on their inner faces with inwardly extending blades, spacing elements provided with shoulders between said plates, and said shoulders of the spacing elements bearing against the inner face of one of the plates, whereby the blades are retained in a spaced position.

In testimony whereof I hereunto affix my signature.

HARRY L. GORDON.
